CLAIM

The ornamental design for an electric toothbrush head, as shown and described.

DESCRIPTION

FIG. 1 is a first perspective view of an electric toothbrush head showing our new design;

FIG. 2 is a second perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the drawings depict portions of the electric toothbrush head in which the design is embodied that form no part of the claimed design.
